APPAREL BAGGING DEVICE

Ashbourne D. Capehart, Oxford, N. C.

Application July 29, 1944, Serial No. 547,265

6 Claims. (Cl. 226—18)

1

This invention relates to garment and apparel bagging devices such as are used in present day clothes cleaning and pressing establishments to place a protective paper bag over and around the garments to promote efficient, safe and early results, and the purpose of the invention is to improve structurally and otherwise upon known types of bagging devices, this through the medium of a novel and structurally improved bagging means.

As the preceding general statement of the invention implies, I am aware that there are many and varied forms of bagging devices patented and in use. Generally speaking, these devices are characterized by a vertical pole or the like suspended perpendicularly from the ceiling, the same having a hook at the lower end thereof, the hook to accommodate the garment hanger, and the pole to accommodate the customarily apertured garment enclosing bag. In accordance with the principles of the instant invention, I provide a pair of companion parallel hook-equipped hanger members, these provided with slides, and the slides in turn provided with special adapter means for insertion in the apertured end of the complementary bag.

More specifically, novelty is predicated upon a pair of complementary vertical suspension members with bag adapter devices slideable on each, these adapter devices being interconnected by a flexible chain, the chain having counterweights, whereby the adapters are alternatively operable, thus making it possible to keep one bag suspended at all times and in readiness to be drawn down over the detachable garment, at which time another bag for subsequent use is drawn up on the other adapter.

Another phase of the invention on which novelty is predicated is the special ceiling fixture and hanger rod suspension means swivelly mounted and provided with a chain accommodation pulley.

Other features and advantages will become more readily apparent from the following description and the accompanying illustrative drawings.

In the drawings, wherein like numerals are employed to designate like parts throughout the same:

Figure 1 is an elevational view of a garment bagging device constructed in accordance with

2

the principles of this invention, one of the bag holding adapter devices being up and the other one down, the first to suspend the bag in elevated position in readiness for use and the other to take on a new bag for elevation.

Figure 2 is an enlarged elevational view detailing the construction of one of the paper bag adapter and holding devices, this being expanded.

Figure 3 is a view like Figure 2 with sleeve 21 at rest in hook 10 thereby causing said adapter device to collapse or fold to either remove a bag or to place a bag in position, as is obvious.

Figure 4 is a sectional view of the counterweights.

Figure 5 is an enlarged detail section partly in elevation, this being taken approximately on the plane of the line 5—5 of Figure 1.

Figure 6 is a horizontal section on the line 6—6 of Figure 2, looking downwardly in the direction of the arrows.

Figure 7 is a perspective view of one of the adapter elements per se.

Referring now to the drawings by distinguishing reference numerals, it will be observed that 25 the hanger rods or bars are denoted by the numerals 8 and 9. They are duplicates and are substantially rectangular in cross sectional form, as seen in Figure 6. Each rod is provided with a hook 10 which, as is obvious, is adapted to accommodate the usual garment hanger (not shown).

30 The upper ends of the hanger rods, as shown in Figure 1, are screw threaded, as at 11, and these screw threaded ends are passed up and through apertures 11a in a cross-head 12 and are fastened in place by clamping nuts, as illustrated in Figure 1. The cross-head in turn is adjustably secured on a screw threaded shank 13 by way of 35 assembling nuts 14. The lower end of this screw threaded member is provided with a fork or yoke 15 to accommodate the pulley 16. The upper end of the screw threaded shank is swivelly mounted, as at 17 (see Fig. 5) in a coupling 18 threaded on the lower end of the ceiling fixture or pipe 19. Thus, the two hanger rods are disposed in spaced 40 parallelism and the entire crosshead structure is swivelly mounted, this in conjunction with the pulley. The pulley serves to accommodate one of the chains 20.

45 Each bag hoisting and lowering assembly is the same and the construction of one will suffice for 50

50

both. The assembly comprises a rectangular sleeve 21 which is shown in Figure 6 as provided with a pair of outstanding ears 22 coacting with similar ears 23a formed by the end extensions of the metal strap 23 connected to said sleeve. These ears serve to accommodate the L-shaped adapter elements 24 (see Fig. 7). Each element comprises a long limb 25 with a deflected free end portion 26 and a short limb 27 terminating in an eye 28, the limbs having a connective web 29 at their adjoining ends. The web serves as a reinforcing element and is also apertured, as at 30 (see Fig. 7), to accommodate a pivot pin 31 which passes therethrough and through the ears 22 and 23a, as shown in Figure 6. Then, as shown in Figures 2 and 3, flexible cords 32 are connected with the adjacent chain ends and with the adjacent eyes 28. By thus pivotally mounting the L-shaped adapter elements 24 on the sleeve and connecting same with the raising and lowering chains, said elements are allowed to either contract into folded position, as shown in Figure 3, or expand to the distended position shown in Figure 2. I also call attention to the ball weights 33 (see Fig. 4) which are linked together and included in the chain arrangement. The aggregate weight of the ball weights combined is such as to overcome friction and weight of the chains and sleeves and adapter devices as well as the paper bag. That is to say, with the ball weights in the position shown in Figure 1, they serve to hold one sleeve and the adapter element 24 in an elevated position with the bag suspended thereon.

In operation it is to be assumed that a paper bag (not shown) has been elevated on the hanger rod 9 and is in suspended position, as shown at the right in Figure 1. This bag is then in readiness for use. Consequently, after the garment hanger is placed on the hook 10, in the usual way, the bag is grasped and pulled down and slipped over the garment. Prior to this, another bag, that is, the second bag, has been slipped up over the adapter means on the left rod 8. Consequently, as the elevated bag is being pulled down, the chains 20 and weights 33 go up. Moreover, the then collapsed adapter devices 24 expand into the bag and take the position seen in Figure 2 and the bag is elevated. The bag which has been pulled down, of course, serves to collapse or fold the heretofore expanded members 24, after sleeve 21 comes to rest in hook 10 which serves also as a stop for sleeve 21, thus enabling the garment and hanger to be removed in bagged condition, and placing the second-named bag in an elevated position ready for the next operation. This makes the device alternative in action and substantially continuously and ever set for use. Therefore, we have a duplex bagging device with bag adapters of an expansible and contractable type, these connected together by a counterweight equipped chain, all of the parts carefully chosen and coacting to produce the desired results.

Novelty is predicated upon the double or duplex idea of the two rods 8 and 9 with the bagging device on each. Novelty is also predicated on the rods singly, and particularly on the expansible and contractable bag adapter and holding devices, whether they be considered conjointly or singly. Further, novelty is predicated upon the ceiling fixture and swivel mount and cross-head arrangement to accommodate both rods 8 and 9, and pulley and chain arrangement.

A careful consideration of the foregoing description in conjunction with the invention as illustrated in the drawings will enable the reader

to obtain a clear understanding and impression of the alleged features of merit and novelty sufficient to clarify the construction of the invention as hereinafter claimed.

5 Minor changes in shape, size, materials and rearrangement of parts may be resorted to in actual practice so long as no departure is made from the invention as claimed.

I claim:

1. In a garment bagging device of the class described, a vertically elongated hanger rod provided with a garment hanger hook at its lower end, means for attaching the upper end of said rod to a ceiling or similar support, said rod being rectangular in cross sectional form, a rectangular sleeve slidable on said rod, a pair of L-shaped expandible and contractable bag adapter and holding elements having their intermediate angular portions swingably mounted on opposite sides of said sleeve, and flexible means for expanding and collapsing said elements, said flexible means comprising a pull chain having flexible elements connected with adjacent inner end portions of said L-shaped elements.
- 15 2. In a structure of the class described, a hanger rod of polygonal cross sectional form, a sleeve of corresponding cross sectional form slidable on said rod, said sleeve being provided with outstanding parallel ears, a pair of duplicate L-shaped adapter elements, said elements being hingedly mounted between the ears and disposed in opposed coacting relationship, a chain for actuating the L-shaped elements, and cords between the adjacent chain-end and adjacent short limbs of said L-shaped elements.
- 20 3. In a garment bagging device of the class described, a ceiling fixture, a coupling mounted thereon, a screw threaded shank swivelly mounted in said coupling, a cross-head adjustably mounted on said shank, a pair of hooked hanger rods of duplicate form having their upper ends detachably connected with the ends of said cross-head, together with a fork on the lower end of said shank, a pulley mounted in said fork, a chain trained over said pulley, and bag holding devices 35 slidably mounted on said rods and connected with the ends of said chain.
- 40 4. In a garment bagging device of the class described, a ceiling fixture, a coupling mounted on said shank, a pair of hooked hanger rods of duplicate form having their upper ends detachably connected with the ends of said cross-head, together with a fork on the lower end of said shank, a pulley mounted in said fork, a chain trained over said pulley, and bag holding devices 45 slidably mounted on said rods and connected with the ends of said chain.
- 50 5. In a garment bagging device of the class described, a ceiling fixture, a coupling mounted thereon, a screw threaded shank swivelly mounted in said coupling, a cross-head adjustably mounted on said shank, and a pair of hooked hanger rods of duplicate form having their upper ends detachably connected with the ends of said cross-head, together with a fork on the lower end of said shank, a pulley mounted in said fork, a chain trained over said pulley, and bag holding devices 55 slidably mounted on said rods and connected with the ends of said chain, said chain including a plurality of counterweights in the manner and for the purposes described.
- 60 6. In a garment bagging device, a hanger rod provided with means at its lower end to support conventional garment hangers, means for attaching the upper end of the rod to a ceiling or equivalent fixed support, a sleeve slidable on said rod, a pair of L-shaped bag adapter and holding elements swingably mounted on said sleeve, and means for actuating said elements, said means comprising a pull chain having flexible elements connected with the L-shaped elements.
- 65 7. In a garment bagging device, a fixture adapted to be secured to a ceiling or equivalent stationary support, said fixture including a cross-head adjustably supported in place, a pair of
- 70 75

hanger rods of duplicate form having their upper ends detachably connected with said cross-head, said rods being in closely spaced parallelism and having hooks adapted to accommodate conventional garment hangers, sleeves slidably but non-rotatably mounted on the respective rods, projectible and retractable garment bag-holding and adapter elements hingedly mounted on said sleeves, pull chains connected at their outer ends to the adjacent bag holding and adapter elements 10 on the complemental sleeves, a pulley mounted on said cross-head between the upper end portions of said hanger rods, and interconnected counter-weights linking together the inner ends of said chains, said chains and counter-weights 15 being trained over said pulley.
